CLAIM

The ornamental design for a ring-style wearable electronic device, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front side elevation view of a ring-style wearable electronic device;

FIG. 2 is a rear side elevation view thereof;

FIG. 3 is a left side elevation view thereof;

FIG. 4 is a right side elevation view thereof;

FIG. 5 is a top plane view thereof;

FIG. 6 is a bottom plane view thereof;

FIG. 7 is an isometric view with an open band thereof;

FIG. 8 is an isometric view with a closed band thereof; and,

FIG. 9 is a front elevation view of the LCD panel in use.
